UNITED STATES PATENT OFFICE

CLAUDE M. SMITH, OF MODESTO, CALIFORNIA

ROTARY VALVE FOR INTERNAL-COMBUSTION ENGINES

Application filed April 5, 1923, Serial No. 630,073. Renewed May 28, 1930.

My invention relates to improvements in rotary valves particularly to the type in which a single rotating member controls the admission of fuel to and the discharge of 5 burnt gases from the engine cylinder.

An object of the invention is to provide a valve of the character described, which will cause the valve and the bearing to become simultaneously and uniformly heated 10 throughout their entire length, thus constantly maintaining practically the same degree of expansion or contraction of said members and insuring the proper fit at all times.

15 Another object of the invention is to provide a rotary valve having connected inner and outer shells which may contract or expand independently of each other both laterally and longitudinally.

20 A further object of the invention is to provide a valve of the character described which causes the formation of an effective lubricating medium between the bearing surface of the valve and its seat.

25 A still further object is to provide a valve of the character described which in itself constitutes an intake and exhaust manifold in addition to functioning as a valve.

A further object of the invention is to provide 30 a valve which will permit the use of low gravity fuel for starting the engine as well as running it.

The invention possesses other objects and features of advantage some of which with 35 the foregoing will be set forth in the following description of the preferred form of my invention, which is illustrated in the drawings accompanying and forming part of the specification. It is to be understood, however, that I do not limit myself to the showing made by said drawings and description, as I may adopt variations of the preferred 40 form within the scope of my invention as set forth in the claims.

45 Referring to said drawings:

Figure 1 is a vertical section, partly in elevation, of one form of the valve of my invention incorporated with an internal combustion engine of the multi-cylinder type.

50 Figure 2 is a vertical transverse section of

valve and engine taken on the line 2—2 of Figure 1.

Figure 3 is a view similar to Figure 2, taken in the line 3—3 of Figure 1.

Figure 4 is a fragmentary section on an 55 enlarged scale, of the tolerance flange used for sealing one of the chambers of the valve.

Figure 5 is a longitudinal section of the portion of the valve adjacent and including 60 the exhaust port thereof.

Figure 6 is a perspective view of the casting 65 for the exhaust port.

In the present embodiment of the invention, the valve 2 is incorporated with a vertical multi-cylinder internal combustion engine and is rotatably mounted in a bearing or bore 3 having transverse port openings 4 which communicate with the interior of the cylinders 6. As here shown, the bearing is formed in the head 7 of the engine and is horizontally disposed therein; it is obvious however that the location of its valve may be changed, depending on the type and design of engine to which it is applied, the number of cylinders, and various other factors. 75

The valve proper comprises a cylindrical shell casing 8 extending practically the full length of the cylinder head and provided with a plurality of sets of intake and exhaust ports 9 and 10 associated with each cylinder and adapted to intermittently register with the opening 4. 80

Preferably concentrically arranged within the shell 8 and held in spaced relation with respect thereto is a cylindrical inner shell 12 provided with openings 13 which are aligned with exhaust openings 10 formed in the outer shell. Two chambers or passages 14 and 15 are thus defined by the shells, viz., a straight passage 14 enclosed by the inner shell, and an annular passage 15 formed between the shells. The inner passage 14 is utilized as an exhaust manifold for the cylinders while the outer passage 15 forms the intake manifold. 85

Extending from each opening 10 to its complementary opening 13 is a casing 17 adapted to resiliently engage the corresponding sides of the openings and thereby seal the exhaust chamber from the intake chamber. The casing is formed of a section of 100

cylindrical tubing whose resiliency is such as to cause it to conform to the shape of the openings, when inserted therein. The casing is held properly positioned in the openings by means of small protuberances 18, preferably pressed in the material and engaging the adjacent sides of the shells. Owing to the fact that the exhaust gases are confined within the inner shell and therefore cause the latter to be heated to a comparatively high temperature, while the outer shell, due to having the comparatively cool intake gases on one side and the cooling effect of the water jacket 19 of the cylinder head on the other side, there will ordinarily be a considerable difference in the temperatures of the respective shells. However, such unequal temperature and consequent differences in the expansion and contraction of the respective shells may take place without effecting each other. This is allowed by reason of the fact that the casing 17 connecting the shells is resiliently rather than rigidly engaged. The factor aiding in maintaining the seal of the casing under all conditions is that the exhaust pressure and intake suction on opposite sides of the casing both tend to press the casing against the sides of the opening. The foregoing effect is aided by providing the casing 17 with bevelled edges 21 as shown in Figure 5.

Means are provided for sealing the ends of the intake chamber in a manner which will permit the independent expansion and contraction of the shells previously referred to. As here shown said means comprises tolerance members 23 inserted between the shells and provided with resilient flanges 24 which press radially in opposite directions against the opposed faces of the shells. Pins 25 or the like slidably mounted in and passing through the members 23 and the shells prevents rotative movement of one shell with respect to the other, and still permit the independent expansion and contraction of the shells.

The outer shell and the wall of the bearing or bore in which it rotates are formed of the same materials or materials having the same coefficients of expansion thereby insuring the proper fit between the shell in its bearing at all temperatures; in the present embodiment both of said members are formed of cast iron. Since the casing 17 and tolerance members 23 allow the inner shell to expand independently of the outer shell, the inner shell is preferably constructed of a material having relatively high torsional and tensile strengths so as to provide the valve with the necessary rigidity of structure.

In order to allow either shell to be moved or displaced longitudinally with respect to the other during unequal linear expansion of the shells, the outer shell is formed in

15 spaced longitudinally as at 28. Each of the sections is held on the inner shell entirely independent of the other, and furthermore they are preferably fixed to the inner shell at but one point in their length—which as here shown is effected by the pins passing through the tolerance members. With this construction not only is either shell permitted to telescope on the other, but it provides for 20 independent longitudinal movement of one portion of outer shell with respect to the other. It will thus be clear that practically all tendency to distort the shape of the outer shell is eliminated. In the present embodiment of the invention the separation 28 between the shell sections 26 and 27 is for convenience associated with openings 29 through which the fuel from the pipe 31 is drawn 25 into the intake manifold.

As hereinbefore stated a plurality of sets 35 of intake and exhaust ports of the valve is preferably associated with each cylinder, and as here shown there are provided with each cylinder three of said sets. In this manner the valve is adapted to make one revolution 30 for each three complete power strokes of any one cylinder. In view of the foregoing the valve here illustrated revolves at one-sixth the speed of the crankshaft. As shown in Figure 1, the driving of the valve may be 35 effected by means including a sprocket 32 which may be driven by chain from the crankshaft and is mounted on an extension 33 of the inner shell. Since the engine here illustrated has four cylinders it is apparent that 40 when one exhaust port of the valve registers with the opening communicating with a cylinder, the remaining eleven exhaust ports will be inactive, but will permit the exhaust gases discharged into or confined in the 45 exhaust manifold to come in direct contact with the bearing or bore wall. Due to this direct contact of the exhaust gases with the wall of the bore, whose temperature owing to the cooling system tends to remain lower than 50 the temperature of the outer shell, the temperature of said wall is raised to equal that of the outer shell which is heated largely by 55 radiation from the exhaust gases, it being noted in connection with the foregoing that 60 since the heating of the outer valve shell is thus effected by radiation from the hot exhaust gases and such heating effect reduced by the presence of the circulating fuel the 65 temperature change through which the wall of the bore must be raised to equal that of the said shell, is comparatively small. Another result of this direct contact of the 70 exhaust with the bore or sleeve is that the rise 75 in temperature of the valve shell and sleeve 80 will take place simultaneously and immediately upon the starting of the engine. Still 85 another advantage of the multiplicity of idle ports is that the pressure of the exhaust gas 90 is partially spent against the shell casing 8 95 100

thereby diminishing the upward thrust of the valve against the bearing and preventing any undue wear of the upper portion of the bearing. In this manner it will be clear that a perfect fit of the valve will be invariably maintained and the desired compression in each of cylinders assured.

Lubrication of the portion of the bearing surface between the ports of the valve is insured by providing longitudinal extensions 36 of the intake ports.

It will be noted that the valve of my invention is in effect a self contained intake and exhaust manifold, and by reason of the fact 15 that the intake manifold completely surrounds the exhaust manifold, an effective means of early volatilization of the incoming fuel prior to its entrance into a cylinder, is attained. The further effectiveness of the 20 foregoing is gained through means of the many thin-walled exhaust port casings which are distributed throughout the length and function to instantly transmit the exhaust heat to the fuel. By reason of such readiness 25 on the part of the casings to transmit the exhaust heat, the effects of the exhaust will be communicated to the incoming fuel gases directly with the initial exhaust of gases, thereby permitting the volatilization of the fuel 30 before the walls of the engine have become heated. In this manner the necessity for using more than a priming charge of high grade fuel in starting, is overcome, and enables the engine to operate on low grade fuel 35 almost from the first explosion. In priming the manifold, I preferably introduce the priming mixture under pressure and in the form of a spray into the intake manifold and against the exhaust manifold, said mixture being preferably introduced into the 40 valve through the openings 29, by means of a conduit 34 leading from a container independent of the main fuel supply. As a contributing feature toward better volatilization 45 is the ability of my device to subject the incoming fuel to a high degree of turbulence or agitation, this being accomplished by the contact of the gases with the labyrinth of passages defined by the exhaust ports.

50 While in the present embodiment of the invention, the valve has been adapted for use in connection with an internal combustion engine, it may as a whole or in part be readily adapted for use in connection with air compressors, steam and other engines.

I claim:

1. In a rotary valve for internal combustion engines, a pair of cylindrical shells positioned one within the other and arranged in spaced relation whereby an annular chamber is provided between them, annular tolerance flanges interposed between said shells and resiliently engaged therewith to seal the 60 ends of said chamber, and means associated 65

with said flanges for preventing the rotation of one shell with respect to the other.

2. In combination with a pair of cylindrical shells positioned one within the other and arranged in spaced relation whereby an annular chamber is defined between them, an annular tolerance flange interposed between said shells and resiliently engaged therewith to provide a sealed partition for said chamber, and means associated with said flange 70 for preventing the rotation of one shell with respect to the other.

In testimony whereof, I have hereunto set my hand, at Oakland, this 19th day of March, 1923.

CLAUDE M. SMITH.
